UNITED STATES PATENT OFFICE.

CARL ALOYS GRÜNEWALD, OF HANOVER, GERMANY.

LETTER-FILE.

No. 826,243.

Specification of Letters Patent.

Patented July 17, 1906.

Application filed September 16, 1905. Serial No. 278,760.

To all whom it may concern:

Be it known that I, CARL ALOYS GRÜNEWALD, a citizen of Germany, residing at Hanover, Germany, have invented new and useful Improvements in Letter-Files, of which the following is a specification.

This invention relates to a file for letters and other papers, which will hold the same securely and permit their ready insertion, 10 inspection, and removal.

In the accompanying drawings, Figure 1 is a perspective view of my improved letter-file. Fig. 2 is a similar view with one of the side plates partly drawn out. Fig. 3 is a 15 plan, partly in section, of part of the file; Fig. 4, a section through one of the end plates. Fig. 5 is a perspective view of the file, showing one of the side plates entirely withdrawn. Fig. 6 is a perspective view of a modification. 20 Fig. 7 is a section through the back of a further modification. Fig. 8 is a perspective view of the case for inclosing the file; Fig. 9, a perspective view of a further modification of the file; Fig. 10, a section through the end 25 plate thereof; Fig. 11, a plan of Fig. 10; Figs. 12 and 13 are end views thereof, showing the side plate in its innermost and outermost positions; and Fig. 14, a cross-section of the modification illustrated in Fig. 9.

The numerals 100 indicate the hinged cover of the file, and 101 is the back. To the back 101 are secured a pair of end plates 1, from the top of which extend inwardly rails or flanges 2, having perforations 8. A set of 35 removable leaves 3, between which the letters and other papers are adapted to be confined, are notched or provided at each edge with a lower projection 4, adapted to engage beneath flange 2. The leaves 3 are thus secured to the back in such a manner that they cannot be lifted off the same, while lateral movement is permitted. To clamp the leaves 3 to the back, I provide the latter with a movable longitudinal slide or partition and 40 with a pair of side plates, of which either one or both may be removable. The slide 5 is notched at its ends to form projections that extend beneath flanges 2 and is provided with springs 6, that project over flanges 2. 45 Pins 7, depending from springs 6 and adapted to engage perforations 8, permit the slide to be locked to the end plate 1 at various positions. The leaves 3 are adapted to be clamped between slide 5 and either one of a 50 pair of parallel side plates 9 and 10, with which the back is provided. To facilitate the insertion and removal of the papers when the file is already well filled, either one or both of these plates is made movable. As illustrated, plate 10 is slidably secured to the 50 back by means of arms 11, that engage end plates 1. Hooks 14 15 on parts 1 11, respectively, limit the outward movement of plate 10. A top spring 12, secured to plate 10, forms a continuation of flange 2 when plate 65 10 is drawn out, and thus locks the papers to the plate. The springs 12 by frictionally engaging flanges 2 also serve to hold the plate 10 in its intermediate positions. To side plates 9 and 10 may be hinged covers 70 17, creased to form feet 102, that rest upon covers 100 and support the leaves 3 and the inclosed letters in their open position.

Fig. 6 shows the leaves 3 inclosed within a separate cover 16. The arms 11 are made 75 resilient, so that they may be disengaged from plates 1 and permit the side plate 10 to be entirely disconnected prior to the removal of the filled cover 16.

Fig. 7 illustrates the construction of the 80 back when both side plates 9 and 10 are slideable. Here the arms 11 of such plates are so placed that they may freely pass each other.

In Figs. 9 to 14 the slide 5 is provided with a hinged cover 170, having foot 171, and with 85 end hooks 19, adapted to engage the perforations 8 of flanges 2. Beneath such flanges there are secured to the end walls 1 upright corrugated plates 24, that constitute guides for the hooks and hold the slide in a vertical 90 position. One of the side plates 9 10—viz., the plate 9—is here omitted. The end plates 1 are provided with springs 20, having bent ends or hooks 21. If the side plate 10 is entirely pushed in, the hooks 21 engage the 95 outer side of such plate, and thus hold it in position. To limit the movement of the side plate, it is provided with a slotted flange 23, engaged by a pin 22 of spring 20. The partition 5 is provided with a shoulder 103, while 100 the plate 10 is provided with a similar shoulder 104, which is, however, out of horizontal alignment with shoulder 103. These shoulders constitute jaws, that serve to securely clamp the papers between slide and side plate. 105 The file when closed may be placed in a suitable dust-proof casing 18. (Illustrated in Fig. 8.)

What I claim is—

1. A letter-file provided with a back, a pair 110 of hinged covers, a pair of end plates on the back, a slidable side plate, means for limiting

the outward movement of said plate, a slide, and means for locking the slide to the end plates, substantially as specified.

2. A letter-file provided with a back, a pair of end plates having perforated flanges, a side plate, a slide, and pins on the slide adapted to engage the flanges, substantially as specified.

3. A letter-file provided with a back, a pair of end plates, flanges on the end plates, leaves having projections adapted to engage the flanges, a slide, and means for locking the slide to the end plates, substantially as specified.

4. A letter-file provided with a back, a pair of end plates, flanges on the end plates, notched leaves and a notched slide engaging the flanges, and means for locking the slide to the end plates, substantially as specified.

5. A letter-file provided with a back, a pair of end plates, a slide, means for locking the slide, a movable side plate, hooks for limiting the outward movement of said plate, and means for holding said plate in intermediate positions, substantially as specified.

6. A letter-file provided with a back, a pair

of flanged end plates, a notched slide adapted to engage the flanged end plates, means for locking the slide to the end plates, a slidable side plate, and means for limiting the movement of the side plate, substantially as specified.

7. A letter-file provided with a back, a pair of flanged end plates, a side plate, a notched slide adapted to engage the flanged end plates, means for locking the slide to the end plates, notched leaves engaging the end plates, and a cover inclosing the leaves, substantially as specified.

8. A letter-file provided with a back, a slide, a pair of end plates, a side plate, means for locking the slide to the end plates, a shoulder on the slide, and a shoulder on the side plate which is out of alignment with the shoulder on the slide, substantially as specified.

Signed by me at Düsseldorf, Germany, this 1st day of September, 1905.

CARL ALOYS GRÜNEWALD.
